DESIGN FOR A PIANO

William Zaiser, Rockville Centre, N. Y., assignor
to The Rudolph Wurlitzer Company, De Kalb,
Ill., a corporation of Ohio

Application March 18, 1937, Serial No. 68,262

Term of patent 7 years

To all whom it may concern:

Be it known that I, William Zaiser, a citizen of the United States, residing at Rockville Centre, county of Nassau, and State of New York, have invented a new, original, and ornamental Design for a Piano, of which the following is a specification, reference being had to the accompanying drawing forming a part thereof.

The drawing is a perspective view of a piano embodying my new design.

I claim:

The ornamental design for a piano, substantially as shown.

WILLIAM ZAISER.
